SPOIL TIPPING CONVEYER

John Skelding Lane, Brierley Hill, England

Application February 27, 1939, Serial No. 258,842
In Great Britain May 21, 1938

5 Claims. (Cl. 198—139)

This invention relates to a tipping conveyer for stacking colliery or quarry refuse, crushed stone or gravel, or the like material into piles to form storage banks. The object of the invention is to enable the conveyor to be extended beyond the normal length without having to dismantle the head end as is usually the case. Furthermore, a broad pathway is made sufficiently firm to support the conveyor when it has been extended beyond the supporting legs or standards. This is advantageous since extraneous elements are liable to undermine the conveyor structure and cause its distortion or even collapse.

According to the invention, the tipping conveyor consists of a main jib provided with a telescopically extending jib boom and a supplementary extension jib section or sections adapted to pass over the extending jib boom for connection longitudinally to the end of the main jib whereby the jib boom can be projected through the extension jib section or sections.

In the accompanying drawings:

Figures 1 and 1A are a side elevation of a tipping conveyer showing the main jib and the telescopic extending jib.

Figure 2 is a section on line 2—2 of Figure 1.

Figure 3 is a cross section on line 3—3 of Figure 1.

Figure 4 is a perspective view showing the conveyor jib and telescopic jib extending therefrom.

Figure 5 is an enlarged detail elevational view of the locking means for the jib boom, and

Figure 6 is a plan of same.

In carrying the invention into effect, the conveyor consists generally of a tail belt-storage section 1, a main jib 2, a telescopic jib boom 3 located within the jib 2 and an extension jib section or sections 4.

In the tail belt-storage section 1 is a conveyer belt 5 which after passing over a floating tension drum 6 and driving drum 7, whereby it is sandwiched with varying pressure according to the load, is deflected by a roller 8 and passes upwards to the top side of a storage belt drum 9 rotating in longitudinally slidable block bearings in a guide rail 10, the driving drum 7 being operated by a power unit 11. After passing over the belt drum 9, the conveyer belt 5 passes rearwards under a deflecting roller 12, thence to a floating tail drum 13 rotating in a loaded bogie 14 running in guides 15 in the frame of the tail belt-storage section 1 whereby the tail drum 13 can be moved rearwards to the dotted position indicated. After passing over the tail drum 13, the conveyer belt 55

5 contacts with a reaction roller 16, thence beneath a collecting chute 17 fed with material by an automatic feeder 18 from a hopper 19. By this means, the length of the belt is doubled in the belt-storage section relatively to the length required to be payed out to allow for the extending action of the jib.

The forward run of the belt 5 is supported by transversely troughed idler rollers 20 located at close intervals upon bearers 21 fixed in the upper part of the main jib 2 and frame of the belt-storage section 1 to dish the belt and prevent spillage of material contained thereon. The troughing effect may be obtained by a series of rollers disposed end-on to each other and set in angular relation as shown in Figure 2. The return side of the belt is supported by horizontal rollers or idlers 22 fitted in the jib boom 3, main jib 2 and tail frame.

20 The belt-storage section 1, main jib 2 and extension jib section 4 are pivotally connected by pivot pins 23 so that these members can be raised or lowered through an arc of plus or minus 5 degrees without causing the structure to be 25 come misaligned in a lateral direction from the line of direction originally set. The one pivoted section, can thus be set at an angle to the preceding section, this feature having the advantage that when it is required to start away from the 30 horizontal position, one or more of the sections at some point ahead may rise or fall to angles relatively to adjacent sections. This has the further advantage in allowing for the inclination of the conveyer to be set for a varied acclivity 35 to suit the nature of the site on which the bank is to be formed or to suit the boundary lines of the site.

Within the main jib 2 is located the telescopic jib boom 3 which is formed of channel side members fitted with cross bearers 24 in which are mounted end-on rollers 25 transversely troughed similarly to the rollers 20 and for the same purpose, these rollers 25 carrying the outward running loaded belt 5 when the jib boom 3 is extended forwards from the extension jib section 4. A discharge head 28 is mounted on the end of the jib boom 3 for distributing the spoil.

At intervals upon the inner sides of the main jib 2 are flanged guide rollers 29 engaging with 50 the upper side of the jib boom 3 for guiding same in its slidable movement.

Each of the extension jib sections 4 is provided along their upper edges with trackway rails 30 so that when an extension is required, it can be mounted on detachable bogie wheels and

ride on the rails 30 along the preceding extension jib sections 4 and be hauled to its position in line with the main jib 2 by a steel wire rope operated by a capstan 31 which may be placed at the forward end of the belt-storage section 1. Upon the same shaft as that of capstan 31, a similar capstan may be mounted for paying out the conveyer belt, and a further capstan for extending the telescopic jib boom 3.

The side members of the jib boom 3 are slotted wherein pivoted double-armed catches 32 are mounted to act through a horizontal plane, these catches being subject to springs 33 bearing upon one arm so as to force the other arm into the path of a stop plate 34 on the end strut of the main jib 2 and 4. The object of these catches is to hold the jib boom 3 rigidly in any predetermined extended position and prevent the same tending to slide backwards through the main jib 2 and 4 due to the reaction thrust of the load.

To give extra strength to the structure and at the same time to prevent a smouldering bank from injuring the conveyer belt 5, pressed steel corrugated plates 35 are fitted to the underside of the main jib 2 and 4, and the jib structure as a whole is supported by standards 36.

In practice, when it is desired to extend the jib structure beyond the normal length obtainable by the main jib 2 and projected jib boom 3, the belt 5 is disconnected and run back and the supplementary extension jib 4, devoid of the bottom rollers 27 and plates 35, is moved forward upon the trackway rails 30 of the preceding jib sections 4 and along the jib boom 3 and placed in longitudinal alignment with the main jib 2 and in embracing relation to the jib boom 3.

With this arrangement, the jib boom 3 can be telescoped through the new supplementary extension jib section 4 to the required extent. When this extension jib section 4 is in place, a new length of belt connected up on the top side only is passed over the upper troughing rollers 20 of the main jib 2 and extended jib sections 4, whereupon the lower rollers 27 and plates 35 are replaced.

Each of the rollers assemblies 27 is formed with a tubular centre spindle 27D located by bolt rod 27E passing therethrough and through holes in the frame runners 2, and held in position by nuts 27F threaded on the ends of bolt rod 27E. After securing the rollers 27 in place, the corrugated plates 35 are connected to the frame runners 2 by nuts and bolts 35A spaced at suitable intervals.

What I claim is:

1. A tipping conveyer comprising a plurality of jib sections pivotally connected together in end to end relation, each of said sections having side frames, upper guide rollers and lower support rollers carried by the side frames of each

section, a jib boom telescopically mounted with respect to said sections and being slidable along said guide and support rollers to project beyond the outermost of said sections, and upper troughed belt carrying rollers on said jib sections and jib boom.

2. A tipping conveyer comprising a plurality of jib sections pivotally connected together in end to end relation, each of said sections having side frames, upper guide rollers and lower support rollers carried by the side frames of each section, trackway rails mounted on said side frames, a jib boom telescopically mounted with respect to said sections and being slidable along said guide and support rollers to project beyond the outermost of said sections, and upper troughed belt carrying rollers on said jib sections and jib boom.

3. A tipping conveyer comprising a plurality of jib sections pivotally connected together in end to end relation, each of said sections having side frames, upper guide rollers and lower support rollers carried by the side frames of each section, a jib boom telescopically mounted with respect to said sections and being slidable along said guide and support rollers to project beyond the outermost of said sections, straight lower belt carrying idler rollers on said jib sections and jib boom, and locking means on the jib boom for holding the latter rigidly in any predetermined extended position.

4. A tipping conveyer comprising a plurality of jib sections pivotally connected together in end to end relation, each of said sections having side frames, upper guide rollers and lower support rollers carried by the side frames of each section, a jib boom telescopically mounted with respect to said sections and being slidable along said guide and support rollers to project beyond the outermost of said sections, a discharge head on said jib boom, a conveyer belt operating over said jib sections and jib boom and including a storage section, and means for paying out additional belt from the storage section as required.

5. A tipping conveyer comprising a plurality of jib sections pivotally connected together in end to end relation, protective plates fitted to and covering the underside frame-work of said jib sections, each of said sections having side frames, upper guide rollers and lower support rollers carried by the side frames of each section, a jib boom telescopically mounted with respect to said sections and being slidable along said guide and support rollers to project beyond the outermost of said sections, a conveyer belt operating over said jib sections and jib boom and including a storage section, a driving drum for said belt, and a tension drum in engagement with the storage belt section and movable with respect to the driving drum to regulate the work carrying length of said belt.

JOHN S. LANE.
